PENICILLIN COMPOSITIONS

John O. Bower, Wyncoate, Pa.

No Drawing. Application December 26, 1944,
Serial No. 569,919

4 Claims. (Cl. 167—58)

1

This invention relates to methods and compositions for prolonging the effectiveness of therapeutic and medicinal agents, and for making it possible to produce a given curative and bactericidal effect by the use of a smaller quantity of the agent employed. Although the invention is applicable to various therapeutic and antiseptic agents, it is particularly valuable in connection with penicillin, and for this reason penicillin will be referred to in this specification as illustrating the invention.

It has long been recognized that the body tends to resent the presence of alien substances, even the most salutary remedies, and that it acts to isolate or throw off any substance not of its own making. This is dramatically illustrated in the case of penicillin. Treatment with this remedy requires the administration of relatively large quantities at relatively frequent intervals. Almost 60 per cent of the amount of penicillin introduced intravenously, for example, is thrown off by the kidneys in the urine within the first hour following its injection.

I have discovered that if the penicillin is introduced in the form of a special solution incorporating constituents of animal blood (which solution is more particularly described hereinafter) the penicillin will remain in the body when injected into the blood or muscle or other tissue or placed in a cavity of the body, for instance, the peritoneal cavity, for a much longer interval. I have also observed that it is absorbed more slowly from the surface of the body whether the skin be intact or partially or completely devitalized as in the case of burns or in diseased conditions affecting the skin. It is not possible at this date to state whether the increased effectiveness resulting from administration of penicillin in this way is to be attributed entirely to the fact that it is excreted less rapidly, or whether there is also an actual improvement in the body reaction which still further increases the unit effectiveness of the remedy. It is my belief that this latter possibility is rather strongly suggested by clinical experience. In any event, the fact is that I have attained results by the use of penicillin in admixture with constituents of animal blood which are entirely comparable with those obtained by others who, lacking knowledge of the invention, have found it necessary to administer considerably larger quantities of penicillin and have found it necessary to repeat the treatment at much more frequent intervals.

The penicillin is, as indicated above, administered in the form of an admixture, the other component of which comprises constituents of animal blood. In preparing such an admixture for the treatment of burns and other external wounds, I prefer to employ about 400 to 500

2

units of penicillin to each cubic centimeter of blood constituents. For intravenous injection, from 400 to 1,000 units per cc. may be employed. As a practical matter, as little as 200 units of penicillin per cc. produces a marked healing effect; while, on the other hand, drastic situations may call for the use of as much as 3,000 units per cc. The range of concentration is great, since penicillin is quite readily soluble in the solution herein described.

Animal blood may be regarded as containing four major constituents: red and white blood cells, blood platelets and plasma. An essential characteristic of my invention is that the preparation contains as one component of the admixture the stroma, or structural element, of the red blood cell, in a state of substantially complete physical disintegration. A preferred aspect of the invention deals with separation of the plasma before adding the penicillin to the remaining constituents. When this is done, plasma may subsequently be added to the material in any desired amount, or the material may be used in a substantially plasma-free condition.

In my copending applications, Serial No. 502,503, filed September 15, 1943, and Serial No. 519,686, filed January 25, 1944, a new form of blood cell solution, containing hemoglobin, electrolytes and disintegrated stroma, is disclosed. That solution is particularly advantageous as the other component of the penicillin admixture of the present invention. Those applications contain rather full instructions for preparing blood solutions having the characteristic above referred to, which instructions will be only summarized herein.

Briefly, these solutions are prepared, for preference, from those components of the blood which remain after extraction of the plasma. The extraction is readily effected after centrifuging, by vacuum suction into a sterile ampoule, all but a very small amount of the blood plasma being removed. The remaining blood residue, consisting essentially of red and white blood cells, blood platelets, electrolytes and the small amount of plasma, is then subjected to an extremely rapid and deep-freezing operation. A distinguishing feature of this process is the rapidity with which the mixture or residue is frozen. In practice, this extremely rapid freezing action is most readily secured by immersing a vessel containing the blood constituents in a mixture of Dry Ice and "Sunoco" spirits, this combination affording temperatures in the neighborhood of -70° C. or -80° C. ("Sunoco" spirits is a refined kerosene.) The intense cold so produced will completely disintegrate the blood cell structure in not more than three minutes, if the solution is

in a 30 cc. test tube, and may produce this effect in as short a time as sixty seconds. Results at least equally good may be obtained in as little as seven or eight seconds if a vessel of the same size is immersed in liquid air or in liquid nitrogen; or in a proportionately longer interval if larger vessels are used. However, these last-named refrigerants are somewhat difficult to handle—primarily because of the danger of breaking ordinary laboratory glassware by subjecting it suddenly to such drastic temperature changes. Liquid air, for example, manifests temperatures of the order of -192° C. This breakage can be obviated by the use of stainless steel or similar unbreakable containers. It should also be remembered that liquid air is inflammable, and, therefore, somewhat more dangerous than either liquid nitrogen or solidified carbon dioxide.

The result of this rapid and deep freezing is to completely disrupt the structure of the blood cells and platelets. I have used the term "disintegrate" to describe this phenomenon, which is quite different from the customary breakdown of blood cell structure produced by mild freezing or even without freezing by the addition of distilled water or chemicals. The disintegration produced by the rapid freezing just described reduces the structure of the blood cells so thoroughly that no differentiation between the blood cell liquid (hemoglobin and electrolyte) and the stroma has been observed even under microscopic examination with either the 4 mm. or the 16 mm. lenses. The solution produced is filterable. In fact it has on many occasions been passed through the asbestos pad of the Horm bacteriological filter now commonly employed to remove micro-organisms from contaminated plasma. Pads of this type are known to be more effective than the finest filter papers, and it is astonishing that any such unfilterable material as red blood residue could be so treated as to meet this test. Yet the fact has been verified by chemical analysis and by spectroscopic examination.

It may be that the solution produced is truly colloidal in character. On the other hand, it may even be true that the change effected in the nature of the stroma is such as to render this substance literally soluble, to a greater or lesser degree, in the blood cell content. Since I have been unable to establish with certainty whether the stroma is actually dissolved in the hemoglobin-electrolyte mixture, or whether it is present therein in a colloidal or subcolloidal form, the expression "solution" is used with the intention of embracing either alternative.

Obviously, the actual time required for deep-freezing a given quantum of material will vary, according to the surface area of the vessel in proportion to its volume, the temperature of the coolant, the rate of heat-transfer through the vessel walls, etc. No conventional standard is available as a guide for determining when a sufficiently rapid rate of freezing has been attained. Under the circumstances, it is necessary to use the results of the Dry-Ice method as a standard of reference in defining the nature of the freezing step: that is, as noted above, my invention contemplates effecting a degree of disintegration in the structure of blood cells and platelets equivalent to that produced by immersing a 30 cc. test tube containing a substantially plasma-free blood solution in a mixture of Dry Ice and Sunoco spirits at a temperature of from -70° C. to

-90° C. for an interval of from one to three minutes.

In the two applications mentioned above, I have disclosed more fully the nature of the blood solution described in the foregoing paragraphs, and have suggested several ways in which it can be used. In my copending application, Serial No. 547,318, filed July 29, 1944, there is described a method for desiccating such solutions, containing the hemoglobin, electrolyte and disintegrated stroma, and there are offered suggestions as to ways in which the dry, amorphous powder so produced may be employed. The technique followed in producing this dry powder is analogous to that employed in "lyophilizing" plasma, and involves gradually desiccating the hemoglobin-electrolyte-stroma solution under controlled temperature and vacuum conditions, so as to leave an amorphous residue which is substantially free of moisture.

An important characteristic of the products obtained by all of the quick-freezing techniques discussed is an astonishing resistance to change during storage. The products, whether in powder or in liquid form, will keep without deterioration for much longer intervals than animal blood which has not been subjected to the deep-freeze treatment.

According to the present invention, there are several methods for obtaining the special admixture of penicillin and blood constituents, all involving the employment of blood constituents derived by applying a quick-freezing treatment to human blood.

First, as the preferred method, I freeze and then thaw the blood residue, as described herein, and after it has completely melted, the desired amount of penicillin is added. This admixture is then drawn into a sterile vacuole and re-frozen by a process called "shelling," necessary to proper desiccation. "Shelling" prepares the material for drying efficiently. The vacuole is placed horizontally in a bath of Dry Ice and "Sunoco" spirits and revolved on its axis continuously at an even rate, the solution forming a thin shell on the sides of the ampoule and having a hollow in the middle. The ampoule is then connected to an intake manifold by means of a rubber nipple. The manifold is attached to a condenser with a secondary coil which is in turn attached to a vacuum pump. As the frozen liquid volatilizes it is drawn off and condensed. After 48 hours the ampoule containing the fine dry powder is removed and stoppered under vacuum, using sterile technique.

The resulting preparation may be placed in condition for intravenous injection, for example, by simply adding plasma, or by adding plasma and distilled water, or by adding distilled water alone. The nature of the addition will influence the viscosity of the liquid produced. For external application, the dry powder may simply be sprinkled on the wound, or it may be mixed with plasma and/or water and applied as a liquid or as a paste.

The second method for constituting the admixture is to add the desired amount of penicillin (in aqueous solution for convenience) directly to the hemoglobin-electrolyte-stroma solution, without desiccating that solution. This procedure is advantageous where the product is to be used within a relatively short time—that is, within a matter of several days. This is the procedure usually employed when the solution is used locally, as, for instance, in the treatment of burns. It is frequently advantageous to add plasma or

distilled water to the material prior to intravenous administration.

A third method of constituting the penicillin admixture is to employ a solution which comprises all of the constituents of the whole blood (in contrast to the blood residue), this likewise having been subjected to the drastic freezing treatment outlined above. This admixture also may be desiccated if desired.

In adding penicillin, I prefer to pick up the desired amount, in aqueous solution, with a sterile hypodermic syringe, and add it to the blood constituents by inserting the needle through the rubber stopper of the vacuum ampoule; the solution within expediting the admixture.

Each of the three procedures outlined above has advantages and drawbacks. The desiccated penicillin powder will keep as long as desiccated plasma, that is, indefinitely. Yet performance of the desiccation introduces one more step in the process of preparing the constituents of the blood, and with each added step the difficulty of maintaining complete sterility and preventing oxidation by contact with the atmosphere is increased. The second method, in which the desiccation step is omitted, and the solution is substantially plasma-free, yields a preparation which is stable, but which will in time undergo changes which will vary with the concentration of the solution and the temperature at which it is kept. The third method, using all of the blood constituents, involves waste of energy in the needless freezing of the plasma, which constitutes a large proportion of the total liquid to be frozen and apparently is neither benefitted nor changed by the freezing. Obviously, the greater the volume of liquid to be frozen, the more difficult it is to freeze it to so low a temperature in so short a time as to produce the type of stroma disintegration which is characteristic of this invention. Moreover, solutions comprising all of the constituents of the blood are not as readily handled and shipped because of their bulk, whereas the materials produced by the first two methods are, in effect, concentrates. On the other hand, if need arises on short notice, the third method has obvious advantages, since, in accordance with that method, a large supply of material ready for use is provided in the shortest possible time and with a very minimum of risk of contamination and deterioration.

In connection with this matter of contamination and deterioration, it is emphasized that the greatest care should be taken throughout to keep the blood out of contact with any except sterile surfaces, and to protect it likewise from contact with the atmosphere. To this end, the blood is withdrawn from the donor in the conventional manner, passing through the sterilized needle, an air-tight sterile tube into a conventional blood donor bottle, which is, of course, likewise air-tight and sterile. Where the plasma is to be removed, the blood is centrifuged, maintaining sterile conditions throughout in a manner which is now well understood. The plasma is then removed and the freezing of the blood cell residue is effected in the original donor bottle. After freezing and melting, the content is withdrawn into vacuumized sterile glass vacuoles. The transfer to these vacuoles is made through sterilized needles and sterile rubber tubes of appropriate size. The vacuum previously produced in the vacuole promotes the flow of the solution thereinto. Similar precautions are taken in connection with the desiccating step, if this is performed. In short, I propose a "closed system"

for carrying out all of the steps of my invention up to the point where the penicillin is admixed with the blood components as described.

The sterility resulting from the employment of the "closed system" described just above is not of primary importance insofar as the preparations of this invention, per se, are concerned. The hemoglobin-electrolyte-stroma complex has certain bactericidal properties of its own. When admixed with penicillin or similar therapeutic agents these properties are enhanced. However, a most important new use for the material is available if sterility is preserved as indicated. The hemoglobin-electrolyte-stroma complex can be introduced directly into the abdominal cavity without the least danger of causing irritation in the delicate membranes of the viscera. In abdominal operations, it is customary to wash or paint the surface of the abdomen with antiseptic solutions, before the operation is begun. After the incision is made, it is necessary to place sterile wound drapes, so as to prevent any of the sterilizing agents used on the surface of the skin from reaching the interior of the abdominal cavity. This is because the antiseptic agents commonly used for this purpose are highly irritant to the intestinal tissues, and irritation from this cause may well result in peritonitis or the formation of adhesions. I have found that it is entirely safe to paint the surface of the abdomen with a solution of the type herein disclosed rather than with antiseptic compounds commonly employed. Thereafter the incision may safely be made without the employment of wound drapes, thus effecting a great saving in time and avoiding a potential source of post-operative complications. If necessary or desirable, the solution may be applied to the walls of the incision itself. The advantages of not having to place, adjust, and remove wound drapes will be very obvious to any surgeon. The technique described has been employed in many operations without the development of a single case of suppuration of the deeper tissues or peritonitis. It has been employed experimentally on numerous animal subjects, and in no case have adhesions formed or has peritonitis occurred. This has been demonstrated by post-mortem examination of the abdominal contents of animals sacrificed at varying periods following the operation.

I have discovered that the drastic freezing process greatly improves the curative properties long known to exist in animal blood. Apparently the complete disintegration of the blood cell structure destroys the distinguishing characteristics of the four blood types, so that blood which has been subjected to the treatment which I have invented may be introduced into the body of a patient without regard to the type classification of the patient's own blood. It may be that the increased effectiveness which I have observed in using penicillin in admixture with constituents of blood as herein described is attributable in part to the strongly curative action of animal blood, the red cells of which have been disintegrated by the drastic freezing treatment heretofore discussed.

Remedial agents other than penicillin have been admixed with the hemoglobin-electrolyte-stroma solution above described, and these admixtures have been found to be more efficacious in the treatment of various diseases than the agent alone. Excellent results have followed intravenous injection of admixtures incorporating the solutions of blood constituents referred to and glucose, so also with convalescent peritonitis

plasma. Incidentally, the admixtures referred to may be diluted with normal saline solution to any extent desired. Unusually rapid healing and a substantial reduction in pain follows the application to burns and external wounds of the blood-constituent solution admixed with the mixtures of alkyl dimethyl benzyl ammonium chlorides more fully described in "New and Non-official Remedies," edition of 1944, at page 112. This mixture is commercially available under the trade-mark "Zephiran Chloride," or cetylpyridinium chloride, a quaternary ammonium compound, known under the trade-mark "Ceeprym"; so also where certain of the sulphonamides, particularly sodium sulphathiazole, have been used in forming the admixture.

In short, an admixture of the hemoglobin-electrolyte-stroma solution with each of a number of remedial agents has resulted in an enhancement of the curative and bactericidal effect of the agent used. From the information given it will be apparent to those skilled in the healing arts that a similar improvement in the effectiveness of other healing agents is to be expected upon admixing them with this special blood solution. It will also be obvious that agents which manifest an unfavorable effect upon blood—that is, which are by nature incompatible with human blood, should not be employed. However, very few compounds not compatible with blood are regarded as remedial agents—that is, as belonging to the class of therapeutic materials with which my invention is especially concerned.

Another aspect of this invention, taking advantage of the surprising resistance of these compounds to deterioration, is the possibility of incorporating them in ointments. Various ointment-base formulae have been tried. My present preference is for one incorporating a simple foundation (such as a cerate and/or petroleum jelly) and zinc peroxide, boric acid, and zinc oxide. To such a base, 10% by weight of the hemoglobin-electrolyte-stroma solution (or a corresponding proportion of the desiccated material) is added, in admixture with 600 units of penicillin per cc. The ointment so produced has been applied to lesions of the epidermis as well as the deeper tissues, and healing has uniformly taken place thereafter at a maximum rate. This has been especially marked where the ointment has been used in the treatment of burns, and the more extensive the damage, the more dramatic is the recovery.

Wherever the preparations described herein have been used, I have been impressed with an apparent increase in the body tolerance towards the curative agent employed, and an apparent improvement in the rapidity and certainty of healing. The improvement in a patient's condition, following an intravenous injection of this special red blood material admixed with penicillin does not wear off in the space of a couple of hours, as it does where penicillin alone is used. An almost immediate reduction in pain follows the application of the admixture (especially in ointment form) to burns of any degree, and this effect persists for several hours even in the most serious cases.

There is a definite gain in the treatment which I have developed simply from the fact that the patient need be disturbed less frequently. Add to this the saving in vitality which results from the fact that, because of the decrease in the quantity required, the body expends less effort in throwing off the drug. And if, as I suspect, the form in

which the material is administered results in an enhancement in its effect which is more than a function of the time it remains in the system, there is a great gain in this aspect of the case.

5 It will be seen that economy resulting from the reduction in amount required is but a small factor compared to the other benefits accruing from the present invention.

In conclusion it may be noted that, although the foregoing discussion specifically relates to the treatment of blood which has been citrated (this being standard practice in the taking of blood from donors), it is possible, and under some circumstances may be highly desirable, to subject the 10 pure blood to the treatment which I have invented. This can be safely accomplished if the blood withdrawn from the donor is deep-frozen promptly. The hemoglobin-electrolyte-stroma solution prepared in this way has, according to 15 laboratory investigation, shown a higher proportion of hemoglobin than is found in whole blood to which sodium citrate has been added. It may possess attributes of considerable importance, since it is free of any extraneous material whatsoever, and may, therefore, have an especial usefulness in therapeutic work.

Where disintegration is referred to in the claims, it is to be understood that the term is used to define the condition discussed heretofore, 20 namely, so complete a disruption of the red blood cells that discrete particles of their structure (stroma) cannot be differentiated under examination with the 4 mm. or 16 mm. lenses of an ordinary laboratory microscope.

35 I claim:

1. A solution for therapeutic use incorporating penicillin and the constituents of animal blood remaining after centrifugal extraction of plasma, the preparation being characterized in that the 40 blood stroma which it contains is present in a state of dissolution such that it cannot be visually differentiated from the remaining blood constituents under microscopic examination under the 4 mm. lens.

45 2. An ointment for clinical administration incorporating about 90% by weight of an ointment base and about 10% by weight of the solution of claim 1.

3. The impalpable powder resulting from vacuum desiccation of the solution of claim 1.

50 4. An ointment for clinical administration containing an ointment base and the solution of claim 1.

JOHN O. BOWER.
